UNITED STATES PATENT OFFICE.

WILLIAM J. NOONAN, OF MANSFIELD, MASSACHUSETTS.

METHOD OF HEATING ROTARY CYLINDERS BY ELECTRICITY.

Application filed November 13, 1922. Serial No. 600,627.

To all whom it may concern:

Be it known that I, WILLIAM J. NOONAN, a citizen of the United States, residing at Mansfield, county of Bristol, State of Massachusetts, have invented a certain new and useful Improvement in Methods of Heating Rotary Cylinders by Electricity, of which the following is a specification, reference being had therein to the accompanying drawings.

The invention relates to an improvement in method of electrically heating a rotary cylinder or drum. The object of the invention is to heat the drum by means of electric heating coils which revolve with the drum. The invention may be applied to a rotary hollow cylinder, such as a roaster for cocoa beans, coffee, peanuts, or other purposes, in which it is desired to have the heat operative in the chamber of a hollow cylinder to roast the contents of the chamber, in which case it is preferred to have the heating coils applied to the outer periphery of the cylinder so as not to have the coils come in contact with the contents of the cylinder or interfere with the smooth interior surface. The invention is also adapted to be applied to a roll or cylinder, in which the heat is utilized on the outer periphery, such for instance as a calendering roll. In such case it is preferable to have the outer periphery smooth, and, therefore, it is preferred to have the heating coils secured to the inner periphery of the cylinder. In either case, the drum being of metal, the heat will pass through the wall of the drum from the heating coils, either from the inner side to the outer side or from the outer side to the inner side as the case may be.

The invention will be fully understood from the following description when taken in connection with the accompanying drawings, and the novel features thereof will be pointed out and clearly defined in the claims at the close of this specification.

In the drawings, Fig. 1 is a side elevation of a rotary circuit drum intended as a roaster embodying the invention, the outer covering of asbestos being partly broken away.

Fig. 2 is an end view viewed from the left-hand end of Fig. 1.

Fig. 3 is an end view viewed from the right-hand end of Fig. 1.

Fig. 4 is a view of a cylinder embodying

the invention, the asbestos covering being broken and the mount being omitted to more clearly show the electric connections.

Fig. 5 is a section on line 5—5 of Fig. 1.

Fig. 6 is a section similar to Fig. 5 of a modified form, in which the heating coils are applied to the inner periphery of the cylinder.

Referring to the drawings, there is shown at 1 a hollow cylinder closed at each end and mounted fast on a rotary shaft 2, which is journaled in bearings 3, 4. The shaft is driven by any suitable means. In the drawings, it is shown as driven by a motor 5 through a pinion 17 and gear 18. A plurality of heating coils 6—6^a are secured lengthwise of the shell on its outer periphery. The heating coils are designated alternately as 6 and 6^a. These heating coils may be secured to the shell in any suitable way so as to rotate therewith; for instance, they may be spot-welded or secured by any other suitable means.

Each heating coil has a wire core surrounded by insulation to keep it out of electrical contact with the shell, as otherwise it would make a short circuit. The insulation, although sufficient to prevent the short circuiting, does not prevent the heat from passing through it to an outer covering or jacket which encloses the insulated wire. This jacket is a heat transmitter and becomes highly heated, thereby heating the shell, the jacket being in direct contact with the shell. The details of this heating coil are not shown in the drawings, as a coil of this construction forms no part of the present invention. The shaft 2 is extended through the ends of the cylinder and has mounted fast thereon two collector rings 7—8, respectively.

The current is supplied through wires 9—10 to brushes 11—12, respectively, and the current goes from the brush 11 to the collector ring 7 and from the brush 12 to the collector ring 8. The collector ring 7 is electrically connected to one end of the heating coils 6 as by a wire 13, wire ring 13^a and wires 13^b. In the drawings the connection is thus shown as made at the right-hand end of the cylinder. The collector ring 8 is connected with the heating coils 6^a by wire 14, wire ring 14^a and wires 14^b.

At the opposite end of the shell 1, the

heating coils 6 and 6^a of each pair are connected by a wire 15. Thus the circuit is made through the several heating coils. The heating coils revolve with the shell. The heat is transmitted from the heating coils to the periphery of the cylindrical shell, and as the shell is made of metal it will be heated throughout, thereby heating the inner periphery and heating the chamber within the shell.

The temperature may be regulated by a rheostat or automatic temperature control if desired, but it is not necessary if care is taken to employ the proper number and size of heating coils for the work required. The contents of the chamber of the cylinder or shell will be tumbled about during the rotation of the shell. The heat will be maintained at the desired temperature and the rotation will be continued for the requisite length of time according to requirement for the particular kind of goods being roasted. Suitable doors will be provided to permit access to the interior of the shell to introduce and to discharge the material to be roasted.

A suitable switch 16 is provided for turning the current on and off.

The shell is preferably wrapped with a covering of asbestos 117 to prevent the external radiation of the heat from the cylinder.

In the modification shown in Figure 6, the heating coils 6, 6^a are secured to the inner periphery of the cylinder, the current being transmitted to the heating coils through wires which pass through the end of the shell to the heating coils on the inside in similar manner to that already described for the heating coils on the outside. In this way the outer surface of the shell is left entirely smooth. When used for calendering purposes, the asbestos covering will be omitted. While I have referred to the rotary shell as being a cylinder, I do not intend to limit the claims to a device which is of strictly cylindrical form. It is obvious that the rotary shell may be polygonal in cross section or may have any other configuration. In the specification I have referred to it as being cylindrical and in the drawings have shown a cylindrical form, because that is the usual form of a roaster and of a calendering roll. It is my intention that in the use of the term "rotary cylinder" or "cylindrical shell" it should be construed as meaning a rotary shell of any configuration.

While I have described one method of electrifying the heat coils, I intend to claim broadly a rotary shell having electric heating coils attached thereto whatever may be the particular method of passing the current through the heating coils.

Preferably the cylinder when used as a

roaster has its journals mounted on skeleton framework somewhat above the floor, so as to afford a space on the under side for other mechanism connected with it. As shown in the drawings, the bearing 4 at one end for one end of the shaft is mounted on a standard 118, and the bearing 3 for the other end of the shaft is mounted on a shelf 19, which in turn is supported by the two standards 20-20. These standards 20-20 are spaced apart from each other and afford a clearance space under the cylinder for a car 21 into which the contents of the cylindrical roaster are to be dumped when sufficiently baked or roasted. The roaster is provided with a sort of a hopper 22 which is in the position shown in full lines, Figure 1, when the cylinder is set to receive its load through a chute 23. When it is desired to dump the contents, the hopper will be turned into the dotted line position, as shown in Figure 1, so that the contents will fall into the car 21. Preferably the car is made with a double bottom, the false bottom 24 being in the form of a sieve located above the real bottom 25. A suction pipe 26 is connected up with one end of the car opening into the space between the real bottom and the false bottom, so as to suck out the chaff or dust which there may be in the contents of the car after the beans or other contents of the roaster have been dumped into the car.

If the smoke and chaff is left any length of time in the beans after they have been roasted and dumped into the car the beans will become impregnated with the bad flavor due to the smoke and chaff which will affect the flavor of the bean and of the coffee or cocoa which is made from it. It is important, therefore, that the chaff and smoke should be removed as soon as possible. That is the reason why it is important that the suction device should be connected up with the chamber below the sieve 24 while the car is in position beneath the discharge chute from the roaster so that the suction device may be put into operation immediately after the beans are dumped from the roaster into the car.

What I claim is:—

1. In combination with a rotary drum, an electric heating medium mounted upon and rotating with said drum, means for electrifying the heating medium during the rotation of the drum, a rotary shaft on which said drum is mounted so that the drum rotates with the shaft, means for rotating the shaft, standards in which said shaft is mounted in such manner that the drum is held elevated at some distance above the surface of the floor on which the standards rest and having an open space for the free entrance of a car to a position beneath the drum and the withdrawal of the car at will,

and a suction device which, at will, may be connected with a car when positioned under the drum.

2. In combination with a rotary drum, an electric heating medium mounted upon and rotating with said drum, means for electrifying the heating medium during the rotation of the drum, a rotary shaft on which said drum is mounted so that the drum rotates with the shaft, means for rotating the shaft, standards in which said shaft is mounted in such manner that the drum is elevated at some distance above the surface of the floor on which the standards rest and having an open space for the free entrance of a car to a position beneath the drum and the withdrawal of the car at will, a car provided with an open top and a closed bottom and a reticulated false bottom at some distance above the real bottom thereby forming a chamber between the false and real bottoms, and a suction pipe

which, at will, may be connected with said chamber below the reticulated member when the car is positioned under the drum. 25

3. In combination with a rotary drum, a heating medium connected with said drum, standards in which said drum is mounted in such manner that the drum is elevated at some distance above the surface of the floor 30 on which the standards rest and having an open space for the free entrance of a car to a position beneath the drum and the withdrawal of the car at will, a car provided with an open top and a closed bottom and 35 a reticulated false bottom at some distance above the real bottom thereby forming a chamber between the false and real bottoms, and a suction pipe, which, at will, may be connected with said chamber below the reticulated member when the car is positioned under the drum. 40

In testimony whereof I affix my signature.
WILLIAM J. NOONAN.
